UNITED STATES PATENT OFFICE.

E. B. BIGELOW, OF CLINTON, MASSACHUSETTS.

DELIVERING PARTY-COLORED WARPS IN WEAVING.

Specification of Letters Patent No. 7,982, dated March 18, 1851.

To all whom it may concern:

Be it known that I, E. B. BIGELOW, of Clinton, in the State of Massachusetts, have invented a new and useful 5 Method of Delivering Out the Figuring-Warps in Looms for Weaving Tapestry Carpets, and that the following is a full, clear, and exact description of the same, reference being had to the accompanying 10 drawings, making part of this specification, in which—

Figure 1 is a plan, Fig. 2, a side elevation and Fig. 3, a longitudinal vertical section.

The same letters indicate like parts in all 15 the figures.

As in the weaving of tapestry carpets the figures are produced by warps on which the figure has been printed of such greater length that when taken up to form the pile, 20 the figure shall appear on the face of the cloth of the required proportions, it follows that unless these warps be delivered out in due proportions for given lengths of cloth the figure produced on the cloth will not 25 match. If the figures which are printed on the warps continued of uniform length until woven into the cloth, a positive delivery motion to give out the figuring warps in measured lengths for given lengths of cloth 30 would effect the purpose; but it is found in practice that after the warps have been printed, the printed figures—from some cause or causes not necessary to mention— 35 vary in length, and hence, if delivered out by a positive and unvarying motion, the figures produced on the woven fabric will not match.

The object of my invention is to avoid as far as possible any defect in the figures on 40 the cloth by reason of any irregularity in the printed figures on the warps and to this end—

The nature of my invention consists in the employment of a shifting clamp or clamps 45 which is or are clamped onto the warps at certain determined points in the length of the printed figure, when the said clamp or clamps is or are used in combination with endless belts or their equivalents, which have 50 a given and positive motion to deliver out the figuring warps, the said clamp or clamps having certain determined points of attachment with the belts. By this means the clamp is secured to the warps at the determined points in the length of the printed

figure and then attached to the given points on the belts, so that if the figure on the warps be too long, they will be loose and hence more will be taken up in forming the pile, and if too short they will be drawn 60 tight and less will be taken up, thus insuring the production of figures that will match.

The accompanying drawings represent my improvements as applied to a loom for 65 weaving cut pile fabrics double, with only so much of the loom as is necessary to show the connection of my improvement with the loom. In these drawings *a* represents the frame, *b* the lathe, *c* the lathe shaft, *d d* the 70 two ground warps, and *e* the arrangement of parts for cutting the pile and taking up the cloths after they have been separated.

There is a frame *f*, jointed to the upper ends of two sets of arms *h, h*, and *i, i* on two rock shafts *j* and *k*, the latter of which has an arm *l* extending down and provided with a wrist fitted to a cam groove *m* on a cam shaft *n* which derives motion from the lathe shaft by cog wheels *o, p*, so that the cam shaft 75 shall make one revolution to three of the lathe shaft; so that every third pick the cam moves the frame toward the lathe and back. The object of this is to carry forward the figuring warps toward the lathe at the time the pile is tied into the cloth, so that the reed shall beat up the pile properly into and between the two cloths, which could not be done so well if the figuring warps were 80 tight at the time.

There are two rollers *q, q*, one at each end of this frame, each carrying a small spur wheel *r* outside of the frame, and the cogs of these wheels engage the threads of two endless screws *s, s*, one at each end of a horizontal shaft *t*, so that the two rollers shall move with the same velocity. This shaft carries a small drum *u* (which is free to turn thereon), to the periphery of which drum is attached a cord *v* that winds around it, the other end being attached to a lever *w*, which is depressed at the required time by a cam or tappet *x* on the cam shaft, so that when the lever is depressed the drum is rotated in one direction, and after the cam has passed, the drum is turned back again by the tension of a spring *y*, to which there is a cord *z* attached that winds around the said drum in the reversed direction of the other cord and also attached to the drum. In 100 105 110

this way the drum receives a reciprocating rotary motion back and forth once for every rotation of the cam shaft.

To one end of the drum there is attached a ratchet hand or pawl α' which engages the teeth of a ratchet wheel β firmly secured on the shaft t so that when the drum is rotated in one direction by the depression of the lever, the shaft will be carried around with it, but not on the return motion. At the rear end this shaft t carries a crank c' to the wrist of which is connected a spring d' , so that after the shaft has been rotated in one direction, it is then held to prevent it from turning back with the drum, and this arrangement also insures the turning of this shaft one entire revolution at each operation without the necessity of turning the drum one entire revolution; for the moment the crank has passed the upper dead point the tension of the spring draws it down to complete the revolution.

By the above arrangement the two rollers on the vibrating frame are caused to rotate to the same extent at each operation. But instead of this arrangement any other mechanical means may be substituted, which will impart the required motion to the rollers. Around the two rollers there pass two bands or belts e' , e' , one near each end which are made to travel by the motion imparted to the rollers. The figuring warps pass from the yarn beam f' and around the seat and over the two rollers g , g . And the bands are pressed onto the forward one of these two rollers by a pressure roller g' , so that they shall only be moved forward by the positive and regular motion of the roller. The warps pass between the jaws of a clamp h' so that it (the clamp) can be clamped onto the warps at any part of their length which may be desired, and then the ends of the clamp are secured to the two bands by fitting onto pins projecting therefrom at the required distance apart to be determined by the figure printed on the warps.

Any given point is selected on the printed figures from which to measure and there the clamp is secured so as to hold all the warps firmly that they shall not slip through, and the clamp is then attached to the belts, and the warps in the process of weaving are then delivered out by the regular and positive motion of the rollers g , g , and belts passing around them, and after the required and determined length has been woven the clamp is loosened and reclamped onto the warps, at the corresponding point in the next printed figure, and the clamp secured to the next

point of attachment on the belts and so on until all the fabric is completed. From the above it will be observed that as the points of attachment of the clamp to the belts are equal distances, and the motion of the rollers and belts is positive, that is, a given and measured length for each tying pick and beat of the lathe, and the woven cloth is taken up by a measured and positive motion,—it follows as a necessary consequence that if the printed figure on the warps be too long, they will be slack between the woven cloth and the clamp and hence will be more freely taken up in the process of weaving, and that if the printed figure be too short less will be taken up, thus throwing the irregularity into the thickness instead of the length of the fabric, producing figures thereon that will match.

In weaving piled fabrics single, to which my said invention is also applicable, the motion of the delivery apparatus toward the latter to yield to the beat thereof may be dispensed with, as in this case the pile is not so long as in weaving such fabrics double, and therefore the yielding motion is not so important.

Instead of the belts passing around the two rollers, two wheels one on each side, and on the same shaft or on separate shafts moving with equal velocity may be substituted, by providing the peripheries of these wheels with the requisite means for attaching the clamps to them, as in the case of the belts. And instead of one clamp two or more may be used by shifting them alternately. And although I have herein pointed out modifications of the mode of application of the principle of my invention, yet I do not wish to be understood as limiting myself to these, as other modes involving the principle or mode of operation of my invention may be substituted.

What I claim as my invention and desire to secure by Letters Patent, is—

The method substantially as herein specified of producing figures that will match on tapestry carpets or other fabrics woven with printed warps by the employment of a clamp or clamps to be clamped onto the warps, as specified, in combination with belts or their equivalents having a positive delivery motion and to which the said clamp or clamps can be attached at given distances, as specified.

E. B. BIGELOW.
